(57) **CLAIM**

The ornamental design for a cutting teeth section for a food zester, as shown and described.

DESCRIPTION

FIG. 1A is a top perspective view of the design for a cutting teeth section for a food zester of the invention;

FIG. 1B is a partial top perspective view of the cutting teeth section for a food zester of FIG. 1;

FIG. 2 is a partial top plan view of the cutting teeth section for a food zester of FIG. 1;

FIG. 3 is a partial front elevational view of the cutting teeth section for a food zester of FIG. 1;

FIG. 4 is a bottom perspective view of the cutting teeth section for a food zester of FIG. 1;

FIG. 5 is an enlarged partial top plan view of the cutting teeth section for a food zester of FIG. 1;

FIG. 6 is an enlarged portion of the top plan view of the cutting teeth section for a food zester of FIG. 5;

FIG. 7 is a partial bottom plan view of the cutting teeth section for a food zester of FIG. 1;

FIG. 8 is an enlarged portion of the partial bottom plan view of the cutting teeth section for a food zester of FIG. 1; and FIG. 9 is an enlarged portion of the top plan view of the cutting teeth section of the food zester of FIG. 8; and, FIG. 10 is a side sectional view, taken along lines 10-10 of FIG. 6, of a cutting tooth of the cutting teeth section for a food zester of FIG. 1.

The broken lines in the figures illustrate portions of the food grater of the invention that form no part of the claim.
